UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,841, dated November 5, 1895.

Application filed September 30, 1895. Serial No. 564,227. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of an arrangement of ornamental scrolls of the style of Louis XVI forming open ornamental panels, with a vase-like ornament filled with flowers and leaves in the center of said panels, as represented in the accompanying drawing.

The border of the design is formed of continuous - running ornamental scrolls with small scrolls and sprays of flowers and leaves attached to said scrolls, as shown in the drawing.

What I claim is—

1. The design for wall paper herein shown and described.
2. In the design for wall paper, the border herein shown and described.

Witness my hand this 27th day of September, 1895.

CHARLES BOOZ.
